UNITED STATES PATENT OFFICE.

STEPHEN A. DOUGLASS, OF ST. LOUIS, MISSOURI.

CHECK-PROTECTOR.

1,285,073.

Specification of Letters Patent. Patented Nov. 19, 1918.

Application filed October 27, 1917. Serial No. 198,814.

To all whom it may concern:

Be it known that I, STEPHEN A. DOUGLASS, a citizen of the United States of America, residing at the city of St. Louis, 5 State of Missouri, United States of America, have invented a certain new and useful Check-Protector, of which the following is such a full, clear, and exact description as will enable anyone skilled in the art to 10 which it appertains to make and use the same, reference being had to the accompanying drawings, forming part of this specification.

My invention relates to a device for making permanent indications of definite or 15 limiting figures on checks or other documents or forms, and the principal object of my invention is to produce a device of this character, which, while thoroughly effective, 20 will be very simple, inexpensive and convenient.

Fundamentally, the invention relates to a device adapted to be removably attached to the cover or other permanent part of a 25 bound volume of checks or other business forms, and provided with means for making indications at the proper place on a form after it is detached. In the specific 30 form herein described the device comprises a one-piece clip formed of resilient material adapted to embrace the edge of a check book cover or the like, and having a resilient part provided with means for tearing out a portion of the check.

35 In the accompanying drawings, which illustrate one embodiment of my invention, Figure 1 is a top plan view of the device; Fig. 2 is a side elevation showing it in place on the edge of a check book cover; 40 Fig. 3 is a plan view of the stamping from which the device is formed by bending the same along the dotted lines; Fig. 4 illustrates a check in position for making an indication of the limiting amount thereon; 45 Figs. 5 and 6 illustrate how, by folding the margin of the check, the device will make an opening in the body of the check, rather than tearing a piece out of the margin as in Fig. 4.

50 As will be apparent from the drawings, the device comprises clamping parts 1 and 2, designed to embrace the edge or other suitable part of a book of check or other forms, and a resilient tongue 3 provided 55 with a V or other suitably shaped point. Pressed out of the part 2 is a resilient re-

taining tongue 5 which bears upon the surface of the book cover 6, and prevents unintentional disengagement of the device therefrom. The stops 4, also integral with the 60 part 2, serve to position the margin of the check in proper relation to the point of the tearing member 3, it being understood that the check forms will be provided with a series of limiting figures or other indications, preferably along a margin of the 65 form. The position of the stops 4 will be so related to the tearing point 3 and the position of the figures with respect to the margin of the check as that when this margin 70 is brought against the stop the member 3 may be caused to make the indication at the proper place.

As a modification, the check form 7 may be provided with a weakened line 8 (Figs. 75 5 and 6) and may be folded along this line before insertion in the indicating device, in which event the device will make a diamond-shaped opening in the body of the 80 check, as indicated in Fig. 6.

In the operation of the device a check which has been filled out is torn from the book and its margin carrying the limiting figures is inserted beneath the tongue 3. This tongue is held down by the operator's 85 finger and the check is pulled toward the tearing point of the member 3 and the portion of the check clamped beneath this point is torn out.

The retaining member 5 is resilient, as is 90 also the material at the bend joining the parts 1 and 2. This permits considerable variation in the thickness of covers 6 to which the device may be satisfactorily attached. It will also be understood that the 95 device may be easily removed from the cover of one check book and transferred to another.

I am aware that modifications may be made in the specific structure illustrated 100 without departing from the spirit of my invention, and I, therefore, do not intend that its scope be limited other than by the accompanying claims.

Having fully described my invention, 105 what I claim as new and desire to secure by Letters Patent of the United States is:

1. The combination of a bound volume of detachable forms, each form being provided with a series of limiting numbers arranged 110 in a row adjacent to the margin and a device for making indications on said forms,

said device comprising a resiliently mounted member attached to a permanent portion of the volume and provided with angularly disposed tearing edges terminating in a 5 tearing point and a stop positioned to co-operate with the margin of a form to locate a limiting number thereon in juxtaposition to the tearing point and to locate said margin in co-operative relation with the tearing 10 edges whereby a portion of the margin may be torn out.

2. A device of the character described, comprising a single piece of resilient material provided with two bends in opposite directions forming it into three spaced superimposed parts with the end members on the outside, one of said parts co-operating with the central part to form a clamp to embrace the edge of a check book cover or the like, 15 and the third part being adapted to co-operate with the central part to make indications on material inserted between said parts.

3. A device of the character described,

comprising a single piece of resilient material bent to form clamping parts to embrace the edge of a check book cover or the like and a third part adjacent to one of said clamping parts for making indications upon the material inserted between it and said clamping part, one of said clamping parts being provided with a stop for positioning the material upon which the indication is to be made.

4. A device of the character described, comprising a single piece of resilient material bent to form clamping parts to embrace the edge of a check book cover or the like, one of said parts being provided with a retaining member bearing upon the cover and 40 with a stop for positioning the material upon which the indication is to be made, and a third part adjacent to the last named part for making indications.

In testimony whereof, I have hereunto set 45 my hand and affixed my seal.

STEPHEN A. DOUGLASS. [L.S.]
